UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

GLOVE AND METHOD OF MAKING THE SAME.

Application filed March 20, 1919. Serial No. 283,743.

To all whom it may concern:

Be it known that I, GEORGE P. BOSWORTH, a citizen of the United States, and a resident of Central Falls, in the county of 5 Providence and State of Rhode Island, have invented an Improvement in Gloves and Methods of Making the Same, of which the following description, in connection with the accompanying drawings, is a specification, 10 like characters on the drawings representing like parts.

This invention relates to gloves and to the method of making the same, and has to do more particularly with long-wristed gloves.

15 The object of the invention is to economically produce, preferably by machine, a glove that will neatly and readily conform to that particular portion of the hand, wrist or arm that it is intended to cover.

20 To the accomplishment of the said objects and such other objects as may later appear, my invention comprises the novel construction and method of producing the same as hereinafter described, and particularly 25 pointed out in the claims, reference being had to the accompanying drawings, wherein is shown a form of glove disclosing my invention.

In the drawings:—
30 Fig. 1 is a perspective view of a glove embodying the features of this invention; and

Fig. 2 is a perspective view of a glove blank from which the glove is made, representing the same as it comes from the machine, and prior to the seaming of the edges thereof.

35 Fig. 3 is a perspective view of a modified form of glove blank wherein the edges of the sections forming the fashioned wrist are selvaged instead of being connected by floating yarns as in Fig. 2.

I shall describe my invention with particular reference to that form of glove which is knitted upon a machine, preferably of the type known as the circular knitting machine, wherein the needle cylinder is capable of being operated either in a continuously rotating manner, or by a rotary reciprocating motion, but it is distinctly to be understood that within the scope and purpose 45 of my invention the glove may be hand knitted or may be formed upon other types of knitting machines than that to which I have previously referred.

50 The invention appertains more particular-

ly to the formation of the arm and wrist portions of the glove, and I shall describe the same preferably as being formed by rotary knitting, although it will be obvious that within the scope and purpose of the invention I am not limited to this particular mode of knitting.

I desire, for convenience, to knit the glove with all of its members integrally formed as, for instance, the hand I preferably knit in 5 a strip in two sections united by a plurality of narrow strips constituting the finger strips of the glove, said two strips constituting the front and back hand coverings.

The thumb, although in the present instance being integrally knit with the front hand strip, may be separately knitted and later applied in any suitable manner to the thumb opening.

Assuming that the glove is to be formed 70 by knitting upon a machine of a circular type having independent needles, it will be evident that while the knitting may commence at any suitable point it should preferably begin at the base of the wrist, either 75 at the front or at the back thereof. Whether the knitting begins at the front or at the back of the bottom of the wrist, the fingers may be knitted in any desired sequence, as, for example, the first, the second, 80 the third and the fourth fingers in the order given, or in the reverse order. I will describe the knitting of the glove as 85 commencing at the base of the wrist at the front thereof, but I am in no wise limited 90 to such mode of procedure.

In the present case, the knitting preferably commences at the front of the wrist and extends from the point 1 across the front of the wrist to the point 2 (see Fig. 95 2), thence back and forth until that portion of the strip constituting the front 3 of the hand is knitted. The needles employed in forming this portion of the glove, are preferably less than one-half of the entire number of needles in the machine. The reciprocating movements, preferably of the needle cylinder, in forming the strip 3, produce selvaged edges 4 and 5 along opposite sides of said strip 3. These reciprocating operations continue until the base 6—6 of the thumb 7 is reached, and since in the present embodiment I am to form the thumb strip integral with the hand, though I am not limited to this construction, I may at the 100 105 110

proper time retain in action the desired number of needles to form the thumb strip 7, while the remaining needles from which the hand strip 3 was formed may be withdrawn from action but be permitted to retain their loops.

In most cases, however, when the base of the thumb is reached, all of the needles are elevated and the desired number to form 10 said thumb strip are brought down into action, and knitting continues on these needles until a strip preferably twice the length of the thumb is formed, when the inactive needles hereinbefore described may again be 15 restored to action and the remaining portion of the hand strip or palm be knitted thereon. The strip constituting the thumb 7 preferably has oppositely selvaged edges which are later seamed together to complete 20 the thumb pocket of the glove.

During the formation of the thumb strip the tip 8 is preferably fashioned upon opposite edges thereof, as indicated at 9—9, by throwing out of action one or, if desired, a 25 plurality of needles, preferably at both ends of each of a series of courses, as, for example, ten courses, such needles retaining their loops and being brought back into operation in the reverse order, thereby widening 30 the fabric and at the same time uniting the edges of the tip along the line indicated by the stitches 9—9, beyond which points the edges of the thumb strip are selvaged and united as previously stated. Within the 35 scope and purpose of my invention the narrowing and widening may be considerably varied. That is, they need not occur on each course but may take place upon selected courses, such, for example, as every second 40 or third course, and again the narrowing may commence at any desired point.

Having completed the formation of the thumb strip, I may, and preferably do, elevate all of the needles employed in forming 45 the thumb strip 7 and then bring down into action all the needles that were employed in knitting said hand strip, and when knitting is continued upon all of said needles the loops at the end of said thumb strip may be 50 knitted into a subsequent course of the hand.

The group of needles employed in forming said strip 7, preferably is set in from the edge 5 of said hand strip, thus leaving 55 a plurality of needles between said group and said edges which are included in the complete group of needles employed in forming the hand strip. This is the preferable arrangement of the thumb strip needles, although it is within the scope and purpose of my invention to vary the position of said thumb strip with relation to the edge of said hand strip.

Having restored to action all the needles 65 that are to be used in knitting the hand

strip of the glove, I next knit the palm 10 of the hand as a flat selvaged strip which terminates at a line 11—12 extending across the hand, and from this line preferably begins the knitting of the finger strips in the 70 order desired.

Preferably I knit integrally with each of the fingers what I term a gusset connecting adjoining fingers, so that each finger is of sufficient size or diameter, although my invention is not restricted thereto. This I preferably do by bringing into action for the knitting of each successive finger certain of the needles used in knitting the preceding finger, as well as those needles which 75 pertain to the knitting of said successive fingers. By this mode of procedure, the fingers are knitted upon a total number of needles exceeding the total number of needles used in knitting the front or the back 80 of the hand. This provides what I term a "lap" of the fingers when the glove is off the hand. It is evident that if the knitting of the fingers be commenced with the little finger, the lap in each case extends toward the 85 first finger, whereas if the knitting begin with the first finger, the lap will in each case extend toward the little finger. I prefer to have the lap extend toward the first finger, and therefore commence the knitting of the 90 fingers with the little finger without, however, in any sense limiting myself thereto.

To continue the knitting from the line 11—12, I now withdraw from action all the needles extending between the points 11 and 12, and then restore to action needles extending from the point 11 to the point 13. Upon these needles I knit a flat strip selvaged 100 upon opposite edges so as to form the front 14 of the little finger, the tip 15 and the 105 back 16 thereof. The tip 15 is preferably fashioned as in the case of the thumb, that is by narrowing and widening, as indicated at 16.

Thus far the knitting operation has completed the formation of the little finger strip down to a line extending from the point 13 at the base of said finger along a line extending between the little and third fingers to the point 17 at the back of the 110 little finger, and thence to the point 18 opposite to the point 11. This completes the knitting of the little finger, and I will next proceed to knit the third finger upon the desired 115 number of needles, but preferably upon an excess number so as to provide the gusset extending from the point 13 to the point 17, and preferably as an integral part of both the third finger and the little finger. I next preferably elevate out of action but 120 retaining their loops all needles used in knitting the little finger strip and then immediately restore those needles extending from the point 17 to the front of the third finger 125 to the point 13 and along the line 11—12, to 130

the point 19 at the opposite side of said third finger, thus including a part of the needles which were used in knitting the little finger.

Upon these needles I knit a flat strip 5 selvaged at opposite edges to form the front 20, the tip 21 and the back 22 of the third finger, fashioning the tip as indicated at 23 substantially as described in connection with the thumb and little finger. Knitting 10 continues on said strip down to a line extending from the point 17 at the base of the third finger to the point 24 and forward between the third and second fingers to the point 19, forming the gusset between said 15 second and third fingers. When this point is reached, the needles which were used in forming said third finger strip are retired but retaining their loops, and certain of these needles and a sufficient number of additional needles are restored to action to knit the strip constituting the second finger of the glove. To this end I therefore bring into action the needles extending from the point 24 to the point 19 and along the line 25 11-12 to the point 25. I now knit by reciprocating knitting upon said series of needles to form a flat strip selvaged at opposite edges constituting the front 26, tip 27 and back 28 of the second finger, the tip 27 thereof being fashioned as indicated at 28' in the manner already described in respect to the preceding digit strips. This operation continues down to a line extending from the point 24 to the point 29 and back 30 to the point 25 at the front of the second finger.

Having completed the knitting of the second finger, I now proceed to knit the strip for the first finger, this being preferably accomplished upon needles previously used in knitting that section of the second finger from the point 25 to the point 29, and in addition to these needles I bring into action a sufficient number of needles to produce the section from the point 25 to the point 12, while all other needles employed in knitting the second finger strip are withdrawn from action. Upon this new set of needles I knit a flat, oppositely selvaged strip constituting the front 30, tip 31 and back 32 of said first finger. The tip 31 of this finger is fashioned at 33 in the same manner as are the other digit members of the glove. This completes the knitting of 45 the first finger strip to a line extending from the point 29 to the point 24 opposite the point 12, and completes the knitting of all of the finger strips.

It will be noted by referring to Fig. 2 60 that the finger strips after being doubled back upon themselves are of different lengths so as to correspond in length with the fingers of the hand, and this result I accomplish by varying the number of 65 courses knitted during the formation of the

several digit strips. That is to say, the formation of the little finger strip will comprise a smaller number of courses from the point 11 to the beginning of the fashioning courses 16, than will the third finger 70 strip from the point 13 to the beginning of the fashioning courses 23, and said third finger strip will be completed in a lesser number of courses than will the second finger strip from the point 19 to the beginning 75 of the fashioning courses 28', and likewise the first finger strip will be formed by a less number of courses from the point 25 to the beginning of the fashioning courses 33 than will the strip of the second finger, which latter strip is the longest of the set.

Having completed the knitting of the first finger strip, I preferably restore to action all of the needles employed in knitting the hand strip 3, including those employed in knitting said first finger strip, and as all of said needles retained their loops when withdrawn from action, these loops will form the basis for the back 35 of the hand 80 covering which I now proceed to knit, said back covering having opposite selvaged edges and being, in length, substantially co-extensive with the front hand covering terminating at 36, 37.

When the line 36-37 is reached in the formation of the glove, the hand and digit portions thereof will have been completed and I next proceed with the knitting of the wrist and arm portions of the glove.

As previously stated, the object of this invention is to produce a fashioned, long-wristed glove, and I will next proceed to describe the preferred method of forming a wrist embodying such characteristics, but it is to be distinctly understood that I am not limited to the particular method about to be described.

When the last course of the back hand strip 35 has been completed, which course 110 is indicated by an imaginary line extending from the point 36 to the point 37, the motion of the needle cylinder is preferably changed from a reciprocatory to a rotary motion, and the needles which formed the 115 back hand strip 35 are retained in action and in addition another series of needles containing substantially the same number are brought into action to form the front portion of the glove wrist from the point 38 to the point 39, and between the end needles of these two series I preferably provide gaps, as indicated by the spaces 36, 39 and 37, 38, upon opposite sides of the glove 120 wrist.

I have stated that the wrist, or, in other words, the fabric formed upon the two series of needles hereinbefore referred to, is produced by rotary knitting, but it is to be distinctly understood that I am not limited to 130

this form of knitting, but may, if I so desire, produce the two sections of fabric by reciprocating knitting and still remain within the spirit and scope of my invention.

6 Nevertheless I preferably effect the production of the wrist by rotary knitting and from a single set of knitting cams, and by reason of this method of construction the edges of the sections of fabric 36, 37 and 10 38, 39 will be connected together by floating yarns or elongated sinker wales 40 and 41, and these sinker wales are preferably reduced in length as the knitting of the wrist proceeds toward the open end of the wrist 15 or arm, so as to gradually increase the width of the front and rear sections 42 and 43 of said wrist.

To accomplish a gradual increase in the width of the front and rear strips I preferably employ picking means for picking into action needles at opposite ends of the series of needles from which said front and back strips are formed. This I may do at the ends of successive courses, or I may effect the knitting of one or a number of courses of the same length between changes, so as to make the increase in width of said strips more gradual.

The gradual increase in the width of the 30 two strips of fabric preferably continues until the largest part of the wrist is reached, as indicated at 44, 45. At these points, the full complement of needles will have been brought into action, and from here on to 35 the end 46 of the glove there will be formed a seamless tube 47 constituting the arm portion of the glove.

This completes one cycle of operations in the production of a single glove, and if 40 desired another glove may be commenced by knitting from the end 46 and upon only a portion of the needles a strip forming the hand portion 3 of the next glove. If desired a light yarn may be used in knitting a few 45 courses before the said next glove knitting is begun, so as to facilitate the separation of the two glove units; or knitting may be continued with the same yarn with or without the formation of a slack course; or at 50 the completion of each glove I may run the same off the needles and start afresh in the formation of the next glove.

It will be evident that if the front and 55 rear sections of the wrist are produced by reciprocating knitting, the V-shaped gaps therebetween will not be spanned by floating yarns or elongated sinker wales, but instead, the edges which are at present connected by said floating yarns, will be selvaged edges.

In Fig. 3 I have illustrated a glove embodying this construction and which has been produced by reciprocating knitting instead of by rotary knitting. Here the edges 60 of the V-shaped gaps which separate the sec-

tions 42', 43' of the wrist have selvaged edges 36', 39' and 37', 38' extending to the points 44', 45', at which points the full complement of needles is used to knit a seamless tube 47'. 70

Furthermore, within the spirit and scope of the invention, the V-shaped gap may be formed at other points than shown in Fig. 2.

Upon completion of the knitting of the blanks, the next operation is to seam together the various edges thereof to form the completed glove. That is, the adjacent edges of the front and rear hand coverings of the blank are seamed together from the bases of the narrowing courses 16 and 33 of the little 75 and first fingers, respectively, to the points 2 and 36 on the little finger side and points 1 and 37 on the first finger side, to form the seams 49 and 50 (see Fig. 1). The inner sides of the first and little finger strips and 80 opposite sides of the second and third finger strips and also opposite sides of the thumb strip, are likewise seamed together and the adjacent edges of the front and rear strips 42 and 43 of the wrist are seamed together 85 as shown at 51 and 52 (Fig. 1) to the points 44 and 45, or, if desired, these seams may, for effect, be extended to the end of the 90 wrist, and the sinker wales 40 and 41 of the blank shown in Fig. 2 subsequently severed 95 from the edges of said strips. The edges connecting the points 1 and 2 of the front hand strip and 38 and 39 of the front wrist portion of the strip may then be stitched together to form a seam 53. 100

Although I have described the several stitching or seaming operations necessary to complete the formation of the glove shown in Fig. 1, it is to be distinctly understood that I do not limit myself to any particular 105 sequence of such stitching operations, as these may be performed in any convenient order.

While I have described the knitting of a glove which is shown in the drawing as a 110 left-hand glove, it is obvious that a right-hand glove may be knitted in any of the ways described with reference to the one disclosed.

Having thus described certain embodiments of my invention, I desire it to be understood that although specific terms are employed they are used in a generic and descriptive sense and not for purposes of limitation, the scope of the invention being set forth in the following claims. 115

1. A knitted glove blank having a strip of fabric constituting the front of the hand, the front and back digit coverings and the back of the hand, and a wrist formed integral with one of said hand coverings in part by reciprocating knitting to provide oppositely selvaged strips to be seamed together and partly by rotary knitting. 120 125

2. A knitted glove blank having hand and 130

digit portions formed in a continuous strip, a fashioned wrist formed in two tapering sections, and a tubular arm knitted integral with and uniting said tapered sections.

5 3. A knitted glove blank having hand and digit portions formed in a continuous strip, a fashioned wrist formed integral with said continuous strip, in two tapering sections, and a seamless tubular arm knitted integral 10 with and uniting said wrist sections.

4. A knitted glove blank having a wrist formed in two gradually widened selvaged webs, and a tubular web uniting the widened ends of said webs.

15 5. A knitted glove blank having hand and digit coverings, a wrist covering knitted in two tapering sections integral with said hand covering, and a tubular section knitted integral with and adapted to unite the large 20 ends of said tapering sections.

25 6. A knitted glove having a selvaged strip constituting front and back hand and digit coverings, a fashioned wrist consisting of two fashioned strips knitted integral with said hand strip, a tubular web uniting the large ends of said fashioned strips, seams to unite adjacent opposite edges of said wrist and hand strips, and a seam extending 30 across the wrist of said glove to unite adjacent edges of said hand and wrist sections.

35 7. The method of forming a glove which consists in knitting a strip constituting the front and back hand and digit coverings, in knitting integral with one end of said strip a fashioned wrist consisting of two gradually widened sections of fabric, in seaming together the adjacent opposite edges of said hand sections and said wrist sections, 40 and in seaming the opposite end of said hand strip to said wrist.

45 8. The method of forming a glove which consists in knitting by reciprocating knitting selvaged strips constituting the front and back hand coverings, in knitting two strips one integral with said hand coverings, upon gradually increasing sets of

needles to form a fashioned wrist, in knitting integral with the large ends of said wrist strips, a tubular section of fabric, and 50 in seaming together the adjacent edges of said hand and wrist sections.

9. A knitted glove comprising single width selvaged front and back hand strips integrally formed at opposite ends of double 55 length, single width digit coverings, a fashioned wrist consisting of two fashioned strips, one of which is knitted integrally with one of said hand coverings, a tubular web uniting the large ends of said fashioned 60 strips, seams to unite adjacent opposite edges of said hand, finger and wrist strips, and a seam uniting the end of the other hand covering with the end of the other fashioned wrist strip. 65

10. A knitted glove blank having single width oppositely selvaged front and back hand strips, single width front and back oppositely selvaged digit strips knitted integral with said front and back hand strips, 70 a wrist formed integral with said hand strips in two fashioned parts corresponding with said front and back hand strips and a tubular arm knitted integral with and uniting said fashioned wrist parts. 75

11. That method of knitting a glove which consists in knitting upon less than half of a series of needles, a strip of fabric constituting the hand and digit coverings of the glove, then in knitting a plurality of 80 courses simultaneously upon the needles employed in knitting said hand covering and another series containing a substantially equal number of needles to knit wrist sections, then in gradually increasing the number of needles at opposite sides of both said series to fashion said wrist sections until all of the needles are in operation, and then in knitting a tubular arm upon all of the needles integral with and uniting said wrist 85 sections. 90

In testimony wherof, I have signed my name to this specification.

GEORGE P. BOSWORTH.
